(57) **CLAIM**

The ornamental design for a data processing equipment as
shown and described.

DESCRIPTION

FIG. 1 is a perspective view of a data processing equipment
showing our new design;

FIG. 2 is another perspective view thereof;

FIG. 3 is another perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

(Continued)

FIG. 9 is a bottom view thereof.
The broken lines depict portions of the data processing
equipment that form no part of the claimed design.

1 Claim, 9 Drawing Sheets
